UNITED STATES PATENT OFFICE.

CHARLES E. SHEDRICK, OF SHERBROOKE, QUEBEC, CANADA.

ELECTRIC CONTROLLER.

No. 881,804.

Specification of Letters Patent.

Patented Sept. 18, 1906.

Application filed August 12, 1905. Serial No. 273,998.

To all whom it may concern:

Be it known that I, CHARLES E. SHEDRICK, a subject of the King of England, residing at Sherbrooke, county of Sherbrooke, Province 5 of Quebec, Dominion of Canada, have invented certain new and useful Improvements in Electric Controllers; and I do hereby declare that the following is a full, clear, and exact description of the invention, such as will enable others skilled in the art to which it 10 pertains to make and use the same.

My invention relates to electric controllers. The object of my invention is to provide an apparatus particularly for electric lights 15 which is simple in construction and automatic in its action.

A further object of my invention is to provide adjustable means for applying the invention to a varying number of electric lights 20 or for similar purposes; and my invention consists of the construction, combination, and arrangement of parts, as herein illustrated, described, and claimed.

In the accompanying drawings, forming 25 part of this application, I have illustrated one form of embodiment of my invention, in which drawings similar reference characters designate corresponding parts, and in which—

Figure 1 is a side elevation. Fig. 2 is a 30 plan. Fig. 3 is a central vertical section taken longitudinally approximately on line 3 3 of Fig. 2, and Fig. 4 is a transverse vertical section taken approximately on line 4 4 of Fig. 2.

Referring to drawings, 5 designates a base, 35 in one corner of which is disposed a binding-post 6, which receives a feed-wire 7. Disposed adjacent the opposite sides of the base are plates 8, on which are disposed standards 9 in electrical connection with the plates. The feed-wire 7 is carried from the binding-post 6 and placed in electrical connection with the plate 8 on one side of the base. The upper ends of the standards 9 are provided 40 with bearings 10, adapted to receive the rockable shaft 11. Disposed on rockable shaft intermediate of the bearings are a plurality of receptacles or cups 12, the periphery of each of which is provided with an opening 45 which may be conveniently closed, as by the screws 12^a. Each of the receptacles 12 is in electrical connection with its adjacent rock-shaft 11, and said receptacles are electrically separated, as by the disk 13, composed of 50 suitable insulation, which also insulates adjacent ends of the rock-shaft.

For the purpose of making electrical connection between receptacles 12 the disk 13 is provided with an opening 14, and each of said receptacles has therein a body of fluid 60 conducting matter 15, preferably mercury. It should be apparent upon an inspection of Fig. 3 that a connection will be made between said receptacles when they are rocked in such position that the mercury can flow 65 through opening 14 and that they will be electrically separated when they are rocked to such a position that the opening 14 is above the level of the mercury. To facilitate making the connection between said 70 cups and to prevent disarrangement of the working of the apparatus by the mercury becoming clogged in said opening, I provide a member 16, disposed through the disk 13 and preferably composed of platinum and of an 75 inverted-U shape, with its ends disposed with relation to the level of the mercury, so that in one position it will not contact therewith and that when in another position it will contact with the mercury, and thereby bridge the 80 insulated space and form an electrical connection between said receptacles.

Carried by one side of the receptacles is a screw-threaded rod 17, adapted to receive the nut 18 and a check-nut 19. Disposed on 85 one end of the base 5 is a standard 20, provided at its upper end with an offset 21, on which is disposed a body of insulation 22, in the path of movement of the rod 17 when the receptacles 12 are rocked.

Projecting from and carried by one side of the receptacles 12 is a rod 23, to which is connected a link 24, carrying a core 25, which is preferably a plate of metal working into a series coil 26, and leading from the coil is a 95 wire 27, carried to the binding-post 28 on the base 5, from whence it is carried on to the lights or place of consumption.

In the operation of my invention the nut 18 and the check-nut 19 are set at such distance on the screw-threaded rod 17 that the electrical current necessary to run a given number of lights will not energize the coil 26 sufficiently to attract the core 25, and thereby rock the receptacles 12 sufficiently to 100 break the connection therebetween. Should more lights be added to the circuit or more current turned on, the coil 26 will be energized sufficiently to attract the core 25, thereby rocking the receptacles until the opening 14 and the conducting members 16 are thrown to the position shown in dotted lines 110

in Fig. 3, whereby the connection will be broken and remain broken until such excess of current is removed. When the excess is removed, the weight of the nut and the check-nut will overcome the attraction of the coil, and the parts will resume the position shown in full lines.

Having thus fully described my invention, what I claim as new, and desire to secure by Letters Patent, is—

1. In a device of the character described, a plurality of rockable receptacles, means for rocking the receptacles, means for electrically separating the receptacles, means for automatically making a connection between the receptacles, and means for adjusting the device to currents of varying intensity, comprising a rod carried by the receptacles and weights adjustably disposed thereon.
2. In a device of the character described, a plurality of rockable receptacles, means for rocking the receptacles, means for electrically separating the receptacles, means for automatically making connection between the receptacles, and means for adjusting a device to currents of varying intensity, comprising a rod carried by the receptacles and screw-threaded weights disposed thereon.
3. In a device of the character described, a

base, conducting-plates on the base, a feed-wire connected to one of the plates, standards on the plates, a plurality of electrically-separated receptacles supported by the standards in electrical connection with the plates, means for making a connection between the receptacles when they are rocked and thereby making a connection between the plates, a coil on the base, means actuated by the coil for rocking the receptacles, means for limiting the movement of the receptacles, and a wire leading from one of the plates into the coil and leading from the coil.

4. In a device of the character described, a pair of electrically-separated plates, standards carried by the plates, a shaft on the standards, means for electrically separating the ends of the shaft, receptacles carried by the shaft on the opposite sides of the separating means and in electrical connection with the shaft, means for bridging the separating means, and means for rocking the shaft to render the bridging means operative.

In witness whereof I have hereunto set my hand in the presence of two witnesses.

CHARLES E. SHEDRICK.
